(57) **CLAIM**

The ornamental design for a tofu press, as shown and described.

DESCRIPTION

FIG. 1 is a right front perspective view of the tofu press in accordance with the present invention with the tofu press in a mostly open position;

FIG. 2 is an exploded left front perspective view of the tofu press of FIG. 1;

FIG. 3 is a top view of the tofu press of FIG. 1;

FIG. 4 is a bottom view of the tofu press of FIG. 1 without a drip tray;

FIG. 5 is a front elevation view of the tofu press of FIG. 1 without a drip tray;

FIG. 6 is a back elevation view of the tofu press of FIG. 1 without a drip tray;

FIG. 7 is a left side elevation view of the tofu press of FIG. 1 without a drip tray;

FIG. 8 is a right side elevation view of the tofu press of FIG. 1 without a drip tray;

FIG. 9 is a bottom perspective view of the tofu press of FIG. 1 without a drip tray;

FIG. 10 is a perspective view of the tofu press in accordance with the present invention with the tofu press in a mostly closed position and without a drip tray;

FIG. 11 is a top view of the tofu press of FIG. 10;

FIG. 12 is a bottom view of the tofu press of FIG. 10;

FIG. 13 is a front elevation view of the tofu press of FIG. 10;

FIG. 14 is a back elevation view of the tofu press of FIG. 10;

FIG. 15 is a left side elevation view of the tofu press of FIG. 10; and,

FIG. 16 is a right side elevation view of the tofu press of FIG. 10.

The broken lines in the drawings depict portions of the tofu press that form no part of the claimed design.
